ELECTRICAL APPARATUS

Richard B. Clark, Sidney, N. Y., assignor to Bé-
dix Aviation Corporation, New York, N. Y., a
corporation of Delaware

Application June 29, 1949, Serial No. 102,120

7 Claims. (Cl. 310—70)

1

This invention relates to electrical apparatus and more particularly to electrical current generating and distributing means adapted for use in internal combustion engine ignition systems or the like.

One of the objects of the present invention is to provide a novelly constructed magneto-generator and associated current distribution means.

Another object of the invention is to provide a novel magneto-generator wherein high efficiency is attained by materially reducing magnetic and electrical losses through eddy currents and the like.

Still another object is to provide a radio-shielded device of the above character which is adapted in a novel manner for water-tight association with an engine.

A further object is to provide a novel magneto-generator and casing combination whereby the operating parts may be removed as a unit, and properly re-installed on the engine with utmost facility and without necessity for readjustment relative to the engine.

A still further object is to provide a magneto-generator or the like which is so constructed as to insure maximum use of the available magnetic flux, whereby the space required for and the weight of a device of given output capacity are reduced to a minimum.

Another object is to provide novel water-tight means on a device of the above character for use in intermittently lubricating an internal part such as a circuit breaker cam.

The above and further objects and novel features of the invention will more fully appear from the following detail description when the same is read in connection with the accompanying drawings. It is to be expressly understood, however, that the drawings are for the purpose of illustration only and are not intended as a definition of the limits of the invention.

In the drawings, wherein like reference characters refer to like parts throughout the several views,

Fig. 1 is a side elevation, mostly in section and with parts broken away and parts removed, of one form magneto-generator embodying the present invention;

Fig. 2 is a detail sectional view taken substantially on line 2—2 of Fig. 3 and showing the stator portion of the magnetic path of the device of Fig. 1;

Fig. 3 is a sectional side elevation of the structure shown in Fig. 2, the section being taken substantially on line 3—3 of Fig. 2;

Fig. 4 is an end view taken from the right

2

side of Fig. 1 with the casing cover and distributor block removed;

Fig. 5 is an end view of the device of Fig. 1, the view being taken substantially on line 5—5 of Fig. 1; and,

Fig. 6 is a sectional view of an oiler for applying a lubricant to the circuit breaker cam of the device of Fig. 1.

The present invention is illustrated in the drawings, by way of example only, in the form of a magneto-generator adapted to supply ignition energy for an eight-cylinder, four-stroke cycle engine when driven at one-half the speed of the engine crank shaft. As shown, the electrical energy creating portion of the device comprises a rotating magnetic flux distributor 10 and a cooperating magnetic flux conducting stator system wholly supported in a novel manner in a two-part housing made mostly of molded insulating material, such as "Bakelite" or hard rubber, which housing or support is in turn mounted in a water-tight radio shielding casing in such a manner as to render the same easily removable. Said housing comprises a hollow cylinder-like member 11 (Figs. 1 to 3) and an end plate or cover 12 therefor (Fig. 1) secured thereto by a plurality of set screws 14 (Fig. 4). Plate 12 may be made of metal, if desired, and may be provided with one or more holes for ventilating purposes.

The stator poles of the magnetic flux conducting system comprise elongated laminated pole shoes 15 and 16 (four in each set), molded into the walls of housing member 11 with one edge 35 surface of each being exposed at the inner periphery of said housing member for cooperation with rotor 10 in a manner to be hereinafter described. The two sets of pole shoes 15 and 16 extend axially of the rotor, those of one set alternating with and overlapping those of the other set, as best seen in Figs. 2 and 3. The left ends of pole shoes 15 and the right ends of pole shoes 16 (as viewed in the drawing), are mechanically and magnetically connected by laminated rings 17 and 18, respectively, which are also embedded in the molded housing member 11. Said rings have integral extensions 19 and 20, respectively, that project radially from the molded housing and serve as seats for the core 21 of a coil 22 (Fig. 1) whereby the magnetic flux circuit is closed or completed. Said coil and core may be suitably secured to rings 17 and 18 by spring clips 23 which engage the upper notched surfaces of the core and the flanges of brackets 24 attached to the sides of extensions 19 and 20.

Rotatably supported in housing 11, 12 by roller

bearings 26 and 27 is the magnetic rotor 10. The latter is of the eight-pole type and comprises an axially magnetized cylindrical magnet 28 with the north and south poles thereof as indicated by the letters N and S or vice versa. The magnet is positioned on a shaft 29 for rotation therewith by a pair of magnetic flux conducting end plates 31 and 32 which are pinned or otherwise suitably secured to the shaft and have axially extending circumferentially spaced pole shoes 33 and 34, respectively, formed integrally therewith. Pole shoes 33 alternate with and extend into overlapping relation with pole shoes 34 as best seen in Figs. 1 and 5. During rotation of the rotor by the engine through splined coupling member 35, the sets of rotor pole shoes 33 and 34 cooperate alternately and simultaneously with the sets of stator pole shoes 15 and 16, thereby making maximum use of the available magnetic flux. In this way the direction of flow of magnetic flux through the magnetic circuit which includes coil core 21 is reversed eight times during each revolution of the rotor, thereby providing for eight spark discharges. The magnet and rotor pole shoe assembly may be further secured to shaft 29 by interposing the same between a shoulder on the shaft and a nut 36 threaded on the shaft.

Shaft bearing 26 and an oil seal 37 of any suitable known construction may be positioned in molded housing member 11 by a ring 38 secured in place by a plurality of threaded bolts 39 which threadedly engage a nut member 40. Bearing 27 preferably has a drive fit in a metal ring molded or cast in cover 12.

The right hand end of shaft 29 extends through bearing 27 and has a combined distributor rotor and circuit breaker cam mounted thereon for rotation therewith. As shown, a flanged hub member 41 is keyed to the shaft and is secured thereon by a nut 42. An insulating disk or cup-like member 43 of hard rubber or the like is secured to the flange of member 41 by bolts 44. The outer periphery of disk 43 is shaped to constitute an eight-lobe cam (Fig. 4) for opening the contacts of a circuit breaker eight times during each revolution of the rotor shaft. The circuit breaker, which is not shown in Fig. 1 in the interest of clarity, may be of any suitable known design and is adjustably mounted on a radially extending portion 45 (Fig. 4) of housing cover 12. In the form illustrated, the breaker comprises a stationary contact 46 engageable by a movable contact 47 mounted on a flexible spring 48 which is actuated by cam 43 through the medium of a metallic cam follower 49 carried by the spring. Although only some of the electrical connections are shown, a condenser 51 is connected in the usual manner in shunt with contacts 46 and 47, one of which is connected to ground and the other to the primary winding of coil 22.

Cam member 43 also serves as the rotary element of an electrical current distributor which includes a distributor block 52 of suitable insulating material. Said block is provided with a center terminal 53 connected through conductors 54 and 55 to the high potential terminal 56 of the secondary winding of coil 22. When the distributor block is secured in position on housing 11, 12, as illustrated, by means of bolts 57, terminal 53 is yieldably engaged by spring contact 58 carried by rotating disk 43. Said contact engages an electrode 59 which moves into spark gap relation with each of eight circumferentially spaced output electrodes 61 circularly arranged in distributor block 52 in a manner well understood

in the art. In the interest of clarity only one of the electrodes 61 is illustrated (Fig. 1).

The parts of the complete magneto-distributor unit described above, including housing 11, 12, 5 rotor assembly 10, 29, 43, circuit breaker 46, 47, condenser 51, and distributor block 52 are secured together and removably mounted in a metallic casing member 62. The latter has an opening 63 in one end thereof which serves as a pilot and support for the cylindrical end portion 64 of housing member 11. A ring 65 of rubber or similar yieldable material is interposed between the inner wall of casing member 62 and a bevelled annular surface 66 on housing member 11 and is surrounded by an internal flange 67 on the casing member. Ring 65 is placed under compression during assembly of the parts and functions not only as a gasket but also as a cushion between the magneto unit and the surrounding casing to absorb shock and vibration.

The other end of the magneto distributor assembly or unit is supported by a plurality of bolts 68 (Fig. 4) which extend through flanges on housing members 11 and 12 and threadedly engage tapped bosses 69 within casing member 62. That portion of the magneto unit not surrounded by casing member 62 is covered by an intermediate casing section 71 and a cover 72 both of which are secured to member 62 by 30 a plurality of bolts 73. If desired, casing section 71 may be integral with member 62.

Each output electrode 61 of the distributor terminates with a spring contact 74 in a tapered recess 75. Resilient adaptor means 76 and a water-tight cover 77 (only partially shown) may be provided for connecting the contacts 74 to outgoing radio shielded spark plug leads 78 and for closing the opening 79 in cover 72 in a water-tight manner. The left end of casing 62 may be 40 adjustably secured to the engine casing (not shown) in a water-tight manner by means of bolts extending through the slotted bosses 61. The water-tight casing thus enables the magneto to operate satisfactorily when the same is immersed in water, such as when the same are installed on submersible and amphibious military vehicles or the like.

Cover member 72 is provided with a receptacle or socket 82 for a radio shielded lead and terminal to connect the insulated side of the circuit breaker and hence, the primary winding of coil 22 to ground through an ignition switch in a manner which is understood in the art. In order to guard against operation of the magneto when the terminal is removed from socket 82, novel means are provided for effecting the electrical connections. Two leaf spring contacts 93 and 94 are mounted on the inner side of cover 72 with the fixed ends thereof insulated from the cover. When the cover 72 is installed spring 94 makes contact with a plate 83 which is connected to the insulated side of the circuit breaker. Spring 93 extends across socket 82 for contact with the terminal (not shown) of the ignition switch lead that extends through fitting 82. When the terminal is removed, contact spring 93 engages cover 72, thereby grounding the coil 22 and rendering the device inoperative. The location of springs 93 and 94 is shown in dotted lines in Fig. 4.

Novel means are provided for applying a lubricant in satisfactory quantities to the surface of cam 43. In the form shown, said oiler is mounted in the wall of casing member 71 in radial alignment with the cam, the same comprising a hollow nut 84 threadedly secured in an opening in cas-

ing member 71. Slidably disposed within nut 84 is a cylindrical container 85 which is closed at one end by element 86 which may be integral therewith. Container 85 is substantially filled with a lubricant saturated wick 87 which projects from the inner end thereof for actuation into contact with cam 43. Unitary means in the form of a bellows 88 are provided for both excluding water and for yieldably holding the parts in position with the wick out of contact with the surface of cam 43. The lower end of the bellows is attached, such as by soldering, to nut 84 and the upper end thereof is similarly attached and mechanically secured to the end 86 of the container. When it is desired to apply a lubricant to the cam surface, it is merely necessary to apply manual pressure in the direction of the arrow, thereby compressing bellows 88 and moving the wick against the cam. Upon release of the pressure the bellows will withdraw the wick away from the cam. Means such as a pin 89 may be provided for holding the wick against movement relative to its container. If desired the space 91 may be filled or partially filled with liquid lubricant. When wick 87 is saturated and pressed against the cam surface, it will leave a spot of lubricant on the latter which will in turn be spread over the surface of the cam by cam follower 49 during rotation of the former. If desired, the wick may be held against the cam while the latter is rotated.

There is thus provided a simple and efficient magneto-distributor of light weight construction which is novelly housed to exclude water even during complete submersion and to provide good radio shielding. Additionally, the casing-magneto unit combination comprehended by the present invention provides for ready removal of the electrical unit from the casing without necessity for disturbing the adjustment of the casing and hence the unit itself relative to the engine and without necessity for access to fastening bolts or the like in the crowded space adjacent the engine.

Although only a single embodiment of the invention is illustrated in the drawings and described in detail in the foregoing specification, it is to be expressly understood that the same is not limited thereto. Various novel features of the illustrated construction could be used in combination with other types of specific elements. For example, other specific types of magnetic rotors or magnetic flux distributors could be employed and other types of distributor constructions could be used without departing from the spirit and scope of the broader aspects of the invention. Other changes could also be made in the size, shape and arrangement of the parts illustrated as well as in the kinds of materials suggested without departing from the spirit and scope of the invention as will now be understood by those skilled in the art. For a definition of the limits of the invention reference is had primarily to the appended claims.

What is claimed is:

1. A magneto generator including a housing comprising a body of insulating material and a cover, magnetic flux conducting stator poles embedded in said body and having extensions projecting from said body, a magnetic flux conducting core connecting said extensions, a coil wound on said core, a magnetic flux distributing rotor mounted in said housing and adapted to cooperate with said stator poles, a metallic casing adapted to be adjustably secured to an engine or

the like, said casing having an opening in the end thereof adjacent the engine for slidably receiving an extension at one end of said housing, and means for supporting the other end of said housing in said casing and for securing the same in predetermined fixed relation within the casing.

2. For combination with an internal combustion engine or the like, a casing comprising a main body portion adapted to be adjustably secured at one end to an engine and removable cover means for the other end of said body portion, an operable self-contained unit comprising an ignition distributor and a magneto generator removably mounted in said main body portion in a predetermined fixed position relative thereto, and means for drivably connecting the rotatable parts of said unit to a driving part of the engine when said unit is mounted in the casing on the engine, said unit being removable from the casing as an operable unit when the casing is mounted on the engine, one end of said casing having an opening of sufficient size to pass said connecting means and the other end being opened sufficiently by removal of said cover means to pass said unit.

3. For combination with an internal combustion engine or the like, a substantially watertight sectional casing adapted to be mounted for angular adjustment on the engine, a magneto generator unit in said casing, said unit including a mass of molded insulation in which metallic parts of the unit are embedded and one end of said unit being supported by a cylindrical extension of said mass slidably engaging an opening in the wall of said casing adjacent the engine, and means removable through the outer end of said casing for supporting the other end of said unit in the casing in a predetermined fixed position therein.

4. In apparatus of the class described, a casing adapted to be adjustably secured on an engine or the like, a unit comprising electrical current generating means removably mounted in said casing in a predetermined fixed position relative thereto, and means for drivably connecting said current generating means to the driving member of an engine, said unit being removable from the casing in operating condition when the casing is mounted on an engine and said casing having an opening in one wall of sufficient size to pass said connecting means and a normally covered opening in another wall of sufficient size to pass said unit.

5. Apparatus as defined in claim 4 wherein said unit includes an electrical current distributor comprising a rotatable part secured to the rotor of the current generating means and a stationary terminal block mounted for cooperation with said rotatable part.

6. Apparatus as defined in claim 4 wherein said unit includes a circuit breaker and electrical current distributing means comprising a rotatable part carrying an electrode and a stationary contact block mounted for cooperation with said electrode, said rotatable part having a cam surface for periodically operating said circuit breaker.

7. For combination with an engine, a sectional casing adapted to be adjustably secured to the engine and including cover means forming the end of the casing remote from the engine, an electrical current generating unit removably mounted in said casing and including a circuit breaker having an insulated terminal, an opening in said cover means for receiving a removable terminal, a resilient contact member mounted on

and insulated from said cover means adapted to engage said insulated terminal when the cover means is in casing-closing position, and resilient contact means having one end electrically connected to said resilient contact member and insulated from said cover means, the other end of said resilient contact means being adapted to electrically engage said removable terminal when the latter is installed in said opening and to electrically engage said cover means when said removable terminal is withdrawn.
